GRINDING APPARATUS

Benjamin O. Isom, Detroit, Mich., assignor to
 Hutto Engineering Company, Inc., Detroit,
 Mich., a corporation of Michigan

Application July 23, 1928, Serial No. 294,668

14 Claims. (Cl. 51—184.3)

This invention relates to devices for finishing cylinder bores or like surfaces and is of that type commonly known as hones or cylinder grinders, the principal object being the provision of a new and novel device of this type which will permit more accurate work to be accomplished by the same.

Another object is to provide a device of the type described wherein the abrasive members may automatically adjust themselves to parallel relationship with respect to the surface being acted upon.

Another object is to provide a device of the type described wherein the means for controlling the diameter across the abrasive members is positive in action.

Another object is to provide a device of the type described wherein the abrasive members are mounted to pivot about a point perpendicular to their length.

Another object is to provide a device of the type described in which the abrasive members are permitted to have a pivotal action about a line perpendicular to their length but which pivotal action is frictionally resisted.

Another object is to provide in combination with a device of the type described, means for preventing undesirable shifting of the abrasive members during operation.

Another object is to provide a new and novel assembly of parts for a device of the type described.

A further object is to provide a new and novel adjusting head for a device of the type described.

The above being among the objects of the present invention, the same consists in certain features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,—

Fig. 1 is a sectional view taken through the axis of the grinder head of a device constructed in accordance with the present invention, the section being taken on a line corresponding to the line 1—1 of Fig. 2.

Fig. 2 is a sectional view taken on the line 2—2 of Fig. 1.

Fig. 3 is a sectional view taken on the line 3—3 of Fig. 1.

Fig. 4 is a perspective view of one of the completely assembled abrasive members.

Fig. 5 is a partially broken and partially sectional side view of an adjusting head for use in connection with the grinder head shown in Fig. 1 taken as on the line 5—5 of Fig. 6.

Fig. 6 is a sectional view taken on the line 6—6 of Fig. 5.

Fig. 7 is a sectional view taken on the line 7—7 of Fig. 5.

Fig. 8 is a sectional view taken on the line 8—8 of Fig. 5.

Fig. 9 is a perspective view of the member which nonrotatably connects the adjusting and driving head to the driving shaft.

Devices of the type herein referred to are commonly employed for finish machining the cylinder bores of internal combustion engines during production thereof, and also for refinishing such bores after they have been worn in service. Although these devices are commonly known as "hones", such name is in reality misleading in view of the fact that they are primarily a grinding device as differentiated from a honing device. Such devices have come into relatively wide use in the past few years. As far as I am aware no device of this type made its appearance in which means are specifically provided to permit the abrasive elements to shift their position along their length relative to the axis of the device.

That is, in the conventional constructions when actuated to increase or decrease their diameters, the base of the abrasive element is maintained in a constant parallel or approximately parallel relationship with respect to the axis of the grinding head. It often occurs that the material at one end of one or more of the abrasive elements may be of softer composition than the other end thereof with the result that the soft end will wear much quicker than the other end, and after a short time in operation only one end of the abrasive element will be doing any substantial amount of grinding.

In accordance with the present invention I provide means whereby each abrasive element may rock in a plane passing through the axis of the grinding head so that such elements may adjust themselves for equal pressure against the surface being ground over their entire length.

Furthermore, as far as I am aware, in none of the devices of this type now on the market is equal contraction of the opposite ends of the abrasive elements insured upon operation of the expanding means therefor. In other words, no means are provided which positively insures equal decrease in diameter of the grinding head over the entire length thereof. The present invention

also provides means whereby this may be accomplished.

Referring to the accompanying drawings 20 represents the body of the grinding head which is provided with an axially extending and axially concentric opening 21. The exterior surface of the body 20 is provided with six equally spaced axially parallel grooves 22, although the number of such grooves may be varied to suit the desires of the particular designer or necessities of the particular object being worked upon as will readily be apparent. Extending radially inwardly from the bottom of each of the grooves 22 and disposed in parallel relationship with respect to the length thereof is a relatively narrow segmentally shaped groove 23, the bottom of which approaches the outer walls of the bore 21. Received within the bore 21 is a member 24 having integrally formed thereon two spaced similarly facing cone surfaces 25 and 26. The body portion 20 is provided with two spaced sets of radially extending openings 27 and 28, each set comprising as many openings as there are grooves 22 and extending radially from the bore 21 to the bottom of one of the grooves 22, the openings 27 and 28 being spaced axially of the body portion 20 an amount commensurate with the axial spacing of the cone surfaces 25 and 26. In each of the openings 27 and 28, a pin 29 is received, the inner surface of which is bevelled in accordance with the angularity of the cone surfaces 25 and 26 and which bears against the corresponding surface of such cone surfaces. The outer ends of the pins 29 are slotted as at 30 in a direction parallel to the axis of the body portion 20, the slots 30 in operation being aligned with the grooves 23. Within each of the inner grooves 23 and received within the slots 30 in the outer ends of the corresponding pins 29 is a segmentally shaped plate member 31. The bottoms of the grooves 30 are formed to conform to the shape of the corresponding inner edge of the plate 31 received therein so that such inner edge of the plate 31 has maximum bearing surface therein in the purpose being to provide frictional contact between the two for a purpose which will be explained later. The outer edges of the plates 31 project into the grooves 22 and received in each of the grooves 22 against the outer edge of each plate member 31 is an abrasive element shown best in perspective in Fig. 4. Each abrasive element preferably comprises an outer channel section member 33 which closely receives therein an inner channel section member 34 which in turn receives and in which is secured the abrasive strip 35. The outer member 33 adjacent its center is provided with two inwardly extending spaced members 36, each of which is provided with an opening 37 at its inner end parallel to the length thereof and each of which is divided midway its length by a slot 38. Each member 33 is slidably received in one of the grooves 22 with the members 36 straddling the corresponding plate 31 and with the bottom of the member 33 bearing against the end portions of the outer edge of the corresponding plate member 31.

In order to prevent axial movement of each abrasive element relative to the body 20, the body 20 is provided with a circumferential groove 40 and each abrasive element is provided with a pin 41 which extends through both the members 33 and 34 and projects out from either side thereof, the pins 41 being of substantially the same diameter as the width of the slot 40, and its projecting ends being slidably received therein.

Where the members 33 are of die cast construction, which may be preferable in some cases, the pins 41 may, in such case, be cast integrally with the members 33 for economy in production. The abrasive elements are maintained against the outer edge of their respective plate members 31, and the plate members 31 are maintained against the bottom of the grooves 30 in the pins 29 in the following manner: A cotter pin 42 is inserted through one of the openings 37 of each of the abrasive elements and an endless coil spring such as 43 is positioned in the groove 40 over each of the cotter pins 42, it passing through the slots 38 in the members 36 of each abrasive element and through the notch 44 provided in each of the plate members 31 for this purpose. It will be apparent that the action of the spring 43 in tending to contract draws the abrasive elements against the plates 31, the plates 31 against the pins 29, and the pins 29 against their respective conical surfaces 25 or 26 as the case may be.

From the foregoing it will be apparent that each plate member 31 which is freely received in its corresponding groove 23 may slide in the grooves 30 of the corresponding pins 29 about the axis of its circular center, and that the abrasive elements will move in accordance therewith. Thus, either end of each abrasive element may shift inwardly or outwardly in order for the outer surface thereof to align itself with the bore of the object being operated upon, regardless of the degree of wear of either end of the abrasive elements. This insures the entire surface of each abrasive element being in contact with the bore of the object being worked upon, with the result that faster and more accurate work may be accomplished thereby. Furthermore, as the grooves 30 in the pins 29 are formed to provide maximum bearing for the curved edges of the plate members 31 received therein, and due to the fact that the members 31 must slide rather than rock in the grooves 30 in order to allow the outer surfaces of the abrasive elements to adjust themselves to the bore being worked upon, sufficient friction is set up between each plate member 31 and its corresponding pins 29, by the pressure of the spring 43, to hold the abrasive elements against inadvertent movement when the grinding head is removed from the bore being worked upon.

Another feature of this construction resulting from integrally connecting the conical surfaces 25 and 26 together is that when the member is shifted axially in the bore 21 to either increase or decrease the effective diameter of the grinding head through the pins 29, a uniform reduction or expansion over the length of the abrasive elements takes place. This is in contradistinction to those conventional types of devices in which the conical surfaces are urged towards proper relation with respect to each other by a spring means which sometimes allows a greater reduction of the diameter at one end of the device than at the other end thereof when the cones are backed off to permit withdrawal of the device from the core of the object being worked upon.

In assembling the grinder head I prefer to place the cotter pins in the opening 37 of each of the abrasive elements which is less advanced in the direction of rotation of the grinding head than the other opening 37. This is for the reason that when there is an appreciable lateral play between the abrasive elements and their respective grooves 22, the pressure of the spring 43 will draw the less advanced edge of the abrasive strip 35 radially

inwardly so that when the grinder head is inserted in the bore to be worked upon and rotated, there will be no danger of the abrasive elements cocking in their grooves and thus inadvertently 5 pressing an edge of the abrasive strip 35 into the wall of the bore so as to cause a tearing or other unevenness of the same such as occasionally occurs in conventional constructions. This same arrangement also prevents chattering of the 10 grinding head. The cotter pins 42 may, of course, be shifted from one of the openings 37 to the opposite opening in accordance with the direction of rotation of the grinding head.

The axial position of the cone member 24 in the bore 21 is controlled in the following manner: The upper end of the member 24, as viewed in Fig. 1 is provided with an internally threaded opening 44, and threaded into the opening 44 is a screw member 45. The body portion of the member 24 is provided with an axially extending groove 46, and a screw member 47 (see Fig. 2) threaded through the body member 20 at the bottom of the slot 40 projects radially into the groove 46, thereby preventing rotation of the member 24 but allowing axial movement thereof within the bore 21. The bore 21 is enlarged as at 49 to provide a shoulder 50 against which a washer 51 seats. The screw 45 rotatably projects through the washer 51 and is provided on the upper side thereof with an enlarged head 52 which is separated from the washer 51 by a plurality of anti-friction balls 53. The head 52 which is maintained against axial movement in a manner which will presently be described is provided with an axially positioned square opening 54 in which a square shaft 55 is received, and the rotatable position of which is controlled, as will hereinafter be explained, to control the rotatable position of the screw 45 relative to the body 20 and consequently the axial position of the member 24 within the bore 21. The anti-friction balls 53 are provided between the head 52 and washer 51 in order to reduce the excessive friction that often occurs at this point when the screw 45 is rotated to draw the cone member 24 upwardly in the bore 21 to increase the diameter over the abrasive elements while the grinding head is in a bore being operated upon.

In devices of this type the grinding head is rotated and moved axially and such movements 50 ordinarily occur simultaneously. The rotational and axial movement of the grinding head in this case is imparted thereto through the hollow shaft 56 in the following manner: The upper end of the body 20 as viewed in Fig. 1 is provided with a spherical seat 57 against which rests a ball 58 formed on the lower end of the shaft 56. The upper end of the body portion 20 is slotted as at 59, and received within the slot 59 on either side of the shaft 56 are the upwardly extending wings 61 of a washer member 62 which overlies the upper end 60 of the opening 49. The ball 58 is diametrically slotted as at 63 and the inner edges of the wings 61 are received in such slots. The wings 61 are thus received in both the slot 59 of the head 20 and the slot 63 of the ball 58, thereby locking the head 20 to the shaft 56 for equal rotation. Split bearing members 64 having spherical seats 65 are received in the upper end of the body 20 in contact with the ball 58 between the wings 61 and are held in position on the head 20 by the cap member 66 to prevent axial movement of the shaft 56 relative to the body 20. The cap member 66 is locked against relative movement by means of the lock nut 67.

Within the opening 49 and surrounding the

head 52 of the screw 45 is a sleeve-like spacer 68, against the upper edge of which the washer 62 is adapted to be clamped by the cap 66 which not only bears against the upper surface of the seat members 64 but also against the upper edges of the wings 61. The spacer 68 is of such a length that the head 52 of the screw member 45 is clamped against axial movement between the washer 62 and washer 51, proper clearance for the balls 53 being taken into consideration. The head 52 of the screw 45 is therefore free to rotate but is positively held against axial movement relative to the body 20. The result is that upon rotation of the screw 45 in either direction, the cones 25 and 26 are given a positive axial movement within the bore 21, and inasmuch as the cones 25 and 26 are integrally connected together the axial movement of each of them is positively assured. This is a marked advantage over any of the conventional constructions of which I am aware due to the fact that in such conventional constructions the cone surfaces when integrally connected together depend upon spring means to move them in one of their directions, or when not integrally connected together depend upon the spring means for movement in one direction. Inasmuch as there is a tendency for the radially extending pins to stick to the cone surfaces it will be apparent that in those constructions depending upon spring means for movement, such friction may at times overcome the force of the spring and thereby cause imperfect action of the device. In fact, this is a common occurrence in conventional constructions and is usually remedied by striking the body of the grinding head with a hammer or other object in order to break the pins loose from the cones. No explanation is necessary to point out the undesirability of such procedure. In the present construction, positive and equal axial movement of the cone surfaces 25 and 26 is assured.

When devices of this type are employed in the production of automobile cylinders it is desirable for economy's sake to be able to accurately adjust the diameter across the outer surfaces of the abrasive elements without stopping rotation of the grinding head. Furthermore, inasmuch as it is necessary to reduce the diameter of the grinding head after grinding one bore and before insertion in another bore, it is desirable to provide means for easily and accurately bringing the effective outside diameter of the grinding head to a pre-determined maximum without stopping operation of the machine. In the present invention means are provided for accomplishing this in the following manner as illustrated in Figs. 5 to 9 inclusive. As indicated in those figures, the control head comprises a body member 72 having an integrally formed tapered driving shank 73 thereon which is threaded as at 74 adjacent its point of connection with the body 72. The lower end of the body 72 is provided with an axially extending opening 75 terminating at its upper end in a spherical seat portion 76. The spherical seat portion 76 is bounded at its upper end by a cylindrical opening 77. A slightly smaller opening 78 extends upwardly from the opening 77 forming a shoulder 79 at the point of junction. A still smaller opening 80 extends upwardly from the opening 78 forming a shoulder 81 at the point of junction. The upper end of the drive shaft 56 is provided with a spherical enlargement 82 which seats against the spherical surface 76 and is held against axial displacement by means of the split seat members 83 whose marginal flange is 75

clamped against the lower face of the body 72 by the flange 84 of the cap 85 which is threaded on to the exterior surface of the lower end of the body 72. The spherical end 82 is slotted as at 86 and the body 72 is diametrically slotted (not shown) from its lower face to the shoulder 79. A washer member 89 is received in the opening 77. This washer member 89 is provided with wing portions 90, as best shown in Fig. 9, in a manner similar to wings 61 on the washer 62 as previously described, the wings 90 being received in the groove 86 of the spherical end 82, and also in the diametric slot just described in the lower end of the body 72 so as to secure the drive shaft 56 to the body 72 for equal rotation therewith. The wings 90 are each provided with an outwardly extending lug portion 91 which project out past the outer surface of the body 72 and are engaged by the nut member 93 which acts to clamp the washer 89 against the shoulder 79.

The nut member 93 may be prevented from rotating relative to the body 72 in the manner indicated in Fig. 5 which is as follows: The cap member 85 is provided with an opening 94 therein positioned parallel to the axis thereof. Within the opening 94 is slidably received a plunger 95 which is constantly urged upwardly by the coil spring 96. The lower face of the nut member 93 is provided with a plurality of depressions 97 which are engageable in turn by the plunger 95, the depressions 97 being equally spaced from the axis of the body member 72.

The construction of the control head thus far described provides means for driving the drive shaft 56 from the spindle 73 through a connection allowing universal movement between the two. The means for controlling the rotatable position of the square shaft 55 which controls the position of the cones 25 and 26 relative to the body member 72 will now be described. The square shaft 55 projects up through the shaft 56, through the washer 89 and into the opening 80. Surrounding the shaft 55 within the opening 78 and non-rotatable relative thereto is a spur gear 98 held against axial movement between the shoulder 81 and washer 89. The body 72 is provided with three equally spaced slots 99 in the same transverse plane as the opening 78, the slots 99 opening into the opening 78, as best illustrated in Fig. 6. Received in each of the slots 99 is a spur gear 100 in mesh with the gear 98. The gears 100 are each maintained in proper spaced relationship with respect to each other by means of axle pins 101 which are rotatably received in the slots 102 extending inwardly from the outer surface of the body 72 perpendicularly to and centrally of each of the slots 99. Rotatably surrounding the body 72 above the nut member 93 is a collar 105. The collar 105 is cut away internally at its lower end as at 106 to provide clearance for the ends 91 of the washer member 89, and also to receive therein and in which is secured an internal gear 107 which meshes with each of the gears 100. The opening 80 is considerably larger than the shaft 55 which is received therein and which shaft receives the gear 98, so that the gear 98 floats between the gears 100, thereby insuring equal turning effort being transmitted by each of the gears 100 to the gear 98. It will be apparent that if the collar 105 is rotated relative to the body 72, the internal gear 107 in rotating with the collar 105 will cause rotation of the gears 100 which, in turn, will cause rotation of the gear 98 and consequently the shaft 55, and that when the shaft 55 is rotated it causes rotation of the

screw 45 in the grinding head and thereby imparts axial movement to the cone member 24 in order to cause an increase or decrease of the effective diameter of the grinding head in accordance with the direction of rotation of the shaft 55. This relative rotation of the collar 105 on the body 72 may be accomplished during rotation of the body 72 by frictionally opposing rotation of the collar 105 simply by grasping the collar 105 by the hand, or else a brake band such as 108 may be provided with suitable means for manually drawing it into contact with the collar 105 to frictionally resist rotation of the latter. However, unless some means were provided for limiting the amount of rotation of the collar 105 relative 15 to the body 72 during rotation of the body 72, as thus described, it will be apparent that it would be impossible to accurately control the maximum diameter to which the grinding head would consequently be expanded. Adjustable means are 20 therefore provided for limiting the relative rotation of the collar 105 relative to the head 72 in the following manner.

The upper surface of the head 72 is provided with a washer member 110 which is secured 25 against rotation relative thereto by screw means such as 111. The washer member 110 projects laterally beyond the surface of the body 72 and bears against the shoulder 112 formed on the collar 105 so as to restrain the collar 105 from 30 movement in that direction. A nut member 113 is threaded on the portion 72 of the spindle 73 and its lower face bears against the washer 110 to thereby lock it against rotation. Rotatably surrounding the nut member 113 is a collar member 35 114. The washer 110 is provided with a relatively great number of openings 115 therein disposed parallel to its axis and all of which are disposed at an equal radial distance from its axis. The collar 114 is provided with a pin member 116 which projects below its lower surface and which is disposed at a distance from the axis thereof equal to the distance of the openings 115 from the axis of the body 72. The pin 116 is of a diameter readily receivable in any one of the openings 115 40 and is normally held in engagement with one of the openings 115 by the plungers 117 which are received within the openings 118 in the collar 114 and are constantly urged upwardly by the springs 119, the plungers 117 bearing against the 45 under face of the flanged portion of the nut 113. If it is desired to change the rotatable position of the collar 114 relative to the head 72, the collar 114 may be raised against the pressure of the spring plungers 117 until the pin 116 is lifted 50 above the washer 110, after which the collar 114 may be rotated to the desired position and the spring plungers 117 then be allowed to project the collar 114 back to its normal position with the pin 116 received in the opening 115 determined 55 by the rotatable position of the collar 114. The collar 114 is further provided with an outwardly projecting lug 120 and the collar 105 is provided with a pin 121 which projects upwardly from its upper surface into the path of the lug 120. From 60 this it will be apparent that inasmuch as the collar 114 is fixed in any one of its rotatably adjustable positions relative to the body 72, the lug 120 is likewise fixed relative to the body 72. The pin 121 in projecting into the path of the lug 120 65 and itself having a relative movement in the plane of the lug 120 limits the rotation of the collar 105 from a position where the pin 121 bears against one side of the lug 120 to a position where it bears against the other side of the lug 120, or, 70 75

in other words, an amount equal to one complete revolution of the collar 105 minus the width of the lug 120 and the diameter of the pin 121.

In actual operation the ratio between the various gears 98, 100 and 107 and the pitch of the screw 45 of the grinding head are so proportioned that the allowable rotation of the collar 105, as limited by the lug 120 and pin 121, is such as to permit the grinding head to be sufficiently contracted after finishing the bore of one object to allow it to be inserted into the bore of the next like object to be worked upon, and then be expanded to the maximum diameter required. By this means, when the device is being employed for grinding a great number of bores of equal diameters such as occurs in the production of automobile cylinders, the collar 105 is rotated to contract the grinding head to the smallest diameter permitted by the position of the lug 120 and pin 121 so that it may be inserted in the bore of the work, and then by frictionally resisting rotation of the collar 105, during rotation of the grinding head, by the brake band 108 or by the hand as described, as great an expansion of the grinding head as the lug 120 and pin 121 will permit is caused in order to obtain the desired maximum diameter of the grinding head necessary for the work being done.

As the abrasive elements 35 of the grinding head wear during the grinding operation, it will be necessary that the position of the lug 120 relative to the body 72, be varied in order to permit a greater expansion of the grinding head to take up the wear, and this is readily accomplished in the manner previously explained by raising the collar 114 against the pressure of the spring pressed plungers 117 and rotating the collar 114 sufficiently to permit the proper additional rotation of the collar 105. Furthermore, the openings 115 in the washer 110 may be so arranged that when the pin 112 is moved from one opening 115 to its next opening 115, the outside diameter of the grinding head will be permitted to increase a definite and easily calculated decimal part of an inch in order that the operator of the device may accurately gauge the increased diameter of the grinding head which will follow in moving the pin 116 from one opening 115 to its next.

From the foregoing it will be apparent that this control means permits the grinding head to be expanded during operation to a predetermined maximum dimension and furthermore permits adjustment of the control so as to maintain such maximum dimension at a constant value in order to compensate for the wear of the abrasive elements.

Formal changes may be made in the specific embodiment of the invention described without departing from the spirit or substance of the broad invention, the scope of which is commensurate with the appended claims.

What I claim is:

1. In a device of the type described, in combination, a body provided with an axially extending bore, a pair of spaced cone members slidably received in said bore, means for controlling the position of said cones in said bore, said body being provided with two series of radially extending openings, a pin slidably received in each of said openings, the outer surface of said body being provided with grooves each of which extends between an opening of each of said series, each of said pins being provided with a groove in line with the first mentioned grooves,

a plate member positioned in each of the first mentioned grooves provided with a curved edge bearing against the bottoms of the grooves in the corresponding of said pins, and an abrasive element bearing against the outer edge of each of said plate members.

2. In a device of the type described, in combination, a body provided with an axially extending bore, a pair of spaced cones slidably received in said bore, means for controlling the position of said cones in said bore, said body being provided with two spaced series of radially extending openings leading into said bore and grooves in its outer surface, each of said grooves extending between an opening of each of said series of openings, said body being provided with a second groove extending inwardly from the bottom of each of the first mentioned grooves, a pin in each of said openings projecting into the corresponding of said second grooves, a segmentally shaped member received in each of said second grooves and slidably bearing on the corresponding of said pins, said members projecting into the corresponding of said first mentioned grooves, and an abrasive element received in said first mentioned grooves in co-operative relationship with respect to the corresponding of said members.

3. In a device of the type described, in combination, a body member provided with an axially extending bore, a pair of fixedly spaced similarly facing cone members slidably received in said bore, radially extending pins carried by said body member having their inner ends bearing one or the other of said cone members, abrasive members supported from the outer ends of said pins, a rotatable member disposed axially of said bore having a screw connection with said cone members, means for positively maintaining said rotatable member against axial movement relative to said body member comprising a pair of abutment surfaces fixed relative to said body member positioned above and below a head on said rotatable member and maintained in fixed spaced relationship with respect to each other by spacing means, and means for rotating said rotatable member.

4. A control head for a grinding head or like device comprising, in combination, a body member, a hollow shaft adapted to be driven thereby, a second shaft within said hollow shaft, a gear non-rotatably secured to said second shaft, a collar rotatably mounted on the outer surface of said body member, an internal gear carried by said collar, and at least three gears interposed in an annular row between said internal gear and the first mentioned gear and in mesh therewith and operating to equalize the transmission of motion from said internal gear to the gear on said second shaft.

5. A control head for a grinding head or like device comprising, in combination, a body member, a hollow shaft adapted to be driven thereby, a second shaft within said hollow shaft, a gear non-rotatably secured to said second shaft, a collar rotatably mounted on the outer surface of said body member, an internal gear carried by said collar, and at least three gears interposed between said internal gear and the first mentioned gear and in mesh therewith, said first mentioned gear floatingly supported between said three or more gears.

6. A control head for a grinding head or like object comprising, in combination, a body member adapted to be driven by a suitable power

means, a hollow shaft secured to said body member for driving movement therefrom, a second shaft within said hollow shaft, a gear secured against relative rotation to said second shaft within said body, said gear supported to float in the plane thereof, a collar rotatably mounted on the exterior of said body member, an internal gear carried by said collar, and three or more gears interposed between the first mentioned gear and said internal gear and supported to float radially of said body member.

7. A cylinder grinder comprising a body provided in its lower end with an upper seat, a bushing arranged in the lower end of said body and provided with a lower seat, a shaft provided with a spherical enlargement engaging the upper and lower seats and an abrasive element operatively connected with said shaft.

8. A cylinder grinder comprising a body provided in its lower end with an upper seat, a bushing arranged in the lower end of said body and provided with a lower seat, a shaft provided with a spherical enlargement engaging the upper and lower seats, a cap connected with said body and engaging said bushing for holding the same in said body and an abrasive element operatively connected with said shaft.

9. A cylinder grinder comprising a body provided in its lower end with an upper seat, a bushing arranged in the lower end of said body and provided with a lower seat, a shaft provided with a spherical enlargement engaging the upper and lower seats, a cap having a screw connection with said body and engaging said bushing, means for preventing rotation of said cap relatively to said body and an abrasive element operatively connected with said shaft.

10. In a cylinder grinder, a body provided in its lower end with an upper seat, a bushing arranged in the lower end of said body and provided with a lower seat, a shaft provided with a spherical enlargement engaging the upper and lower seats, a cap having a screw connection with said body and engaging said bushing, and means for preventing rotation of said cap relatively to said body, including a member arranged on said body and provided with a plurality of depressions, a plunger mounted on said cap and adapted to engage one or another of said depressions, and a spring for pressing said plunger toward said member.

50 11. In a cylinder grinder, a body provided with

a seat and notches on diametrically opposite sides of said seat, a shaft having an enlargement which engages said seat and is provided on its diametrically opposite sides with notches, and a cross piece arranged within the body and provided with a pair of wings engaging with said notches of the body and another pair of wings engaging with the notches of said enlargement.

12. In a cylinder grinder, a body, a shaft connected with said body, a collar rotatable on the exterior of said body, a gearing operatively connecting said collar and shaft, a ring connected with said body and provided with a plurality of openings, a stop collar adjustable about the axis of said body and provided with an adjusting pin adapted to engage with one or another of said openings and also provided with a stop lug, and a stop arranged on said body and adapted to be engaged by said stop lug.

13. In a cylinder grinder, a body, a shaft connected with said body, a collar rotatable on the exterior of said body, a gearing operatively connecting said collar and shaft, a ring connected with said body and provided with a plurality of openings, a stop collar adjustable about the axis of said body and provided with an adjusting pin adapted to engage with one or another of said openings and also provided with a stop lug, a stop arranged on said body and adapted to be engaged by said stop lug, and means for yieldingly retaining said adjusting collar in operative relation to said body and ring.

14. In a cylinder grinder, a body, a shaft connected with said body, a collar rotatable on the exterior of said body, a gearing operatively connecting said collar and shaft, a ring connected with said body and provided with a plurality of openings, a stop collar adjustable about the axis of said body and provided with an adjusting pin adapted to engage with one or another of said openings and also provided with a stop lug, a stop arranged on said body and adapted to be engaged by said stop lug, and means for yieldingly retaining said adjusting collar in operative relation to said body and ring, including an annular abutment connected with said body, plungers mounted on said adjusting collar and engaging with said abutment, and springs urging said plungers toward said abutment.

BENJAMIN O. ISOM. 50
